J. F. DUBY.

VALVE SPRING LIFTER.

APPLICATION FILED DEC. 17, 1919.

1,365,468.

Patented Jan. 11, 1921.

UNITED STATES PATENT OFFICE.

JOHN FABIEN DUBY, OF BOSTON, MASSACHUSETTS.

VALVE-SPRING LIFTER.

1,365,468.

Specification of Letters Patent. Patented Jan. 11, 1921.

Application filed December 17, 1919. Serial No. 345,526.

To all whom it may concern:

Be it known that I, JOHN F. DUBY, a citizen of the United States, residing at Boston, in the county of Suffolk and State 5 of Massachusetts, have invented new and useful Improvements in Valve-Spring Lifters, of which the following is a specification.

The object of this invention is to provide a simple and effective tool for lifting the 10 spring on the stem of a puppet valve and thus permitting the removal of the usual spring-supporting pin or key in the valve stem preparatory to the removal of the valve, the object being particularly to enable 15 the force exerted by the operator in lifting the spring to be sustained directly by the valve, and not directly by a fixed support on the engine.

The invention consists in the improvements which I will now proceed to describe 20 and claim.

Of the accompanying drawings forming a part of this specification,—

Figure 1 is a view showing the valve 25 chamber of an internal combustion engine and the valve spring in section, the valve and its stem in elevation, and a spring lifter embodying the invention also in elevation.

Fig. 2 is a section on line 2—2 of Fig. 1, 30 and a plan view of a portion of the lifter.

Fig. 3 is a view similar to Fig. 2, showing the stem-receiving recess of the inner jaw widened.

Fig. 4 is a view similar to Fig. 2, showing 35 a modification.

Fig. 5 is a side elevation on a smaller scale, showing a different embodiment of the invention.

I will first describe the invention as shown 40 by Figs. 1, 2, 3 and 4.

In the drawings, *a* represents an ordinary puppet valve normally held against its seat *b* by a spring *c* which is seated at one end on a fixed abutment *e*, and at the other end 45 one a washer *f*, supported by a key or pin *g*, removably inserted in an orifice in the valve stem *h*.

My improved spring lifter includes an outer jaw adapted to be seated on the closed 50 valve when the latter is exposed by the removal of a plug from an opening *i* in the valve chamber, so that the outer jaw is supported by the valve, and an inner jaw adapted to lift the spring from the key *g* when 55 the outer jaw is seated on the valve. Said

outer jaw, in the preferred embodiment of the invention here shown, includes a body portion 12, an arm 13, projecting in one direction from the body portion, and a grip member 14, projecting in an opposite direction from the body portion. The outer jaw also preferably includes an adjustable terminal 15, formed to pass through the opening *i*, and bear on the valve *a*. Said terminal may be a screw-threaded bolt, having 60 a pointed inner end 16 adapted to have a non-slipping engagement with the outer side of the valve, and a head 17 whereby it may be turned, the bolt engaging a tapped orifice in the arm 14. The terminal 15 is, 65 therefore, adapted to be adjusted to vary the space between the two jaws, and adapt the tool for use with different engines. The inner jaw is an arm forming one of the members of a bell-crank lever, and is provided with terminal fingers 19 forming a slot or recess 18 adapted to receive the valve stem *h* and its key *g*, as shown by Figs. 2 and 4. Said fingers are preferably adjustable to vary the width of said recess. 70

Figs. 1, 2, and 3 show the inner jaw as including fingers 19, movable toward and from each other. Each finger 19, has an ear 20, provided with an oblique slot 21, one ear overlapping the other, and the slots 21 being in different angular positions. The inner jaw also includes an inner portion 22, which is pivoted at 23 to the arm 13. The fingers 19 are provided with flexible shank portions 24, which are secured by rivets 25 to the arm portion 22. A bolt 26 having a head at one end, and a nut 27 at the other end, passes through intersecting portions of the slots 21.

When said bolt is adjusted, as shown by Fig. 2, the recess 18 has a minimum width, and when the bolt is adjusted, as shown by Fig. 3, the width of the recess is increased. Provision is thus made for accommodating the inner jaw to the size of the valve stem. 95

The inner jaw is provided with an elongated lever arm 30, forming another member of a bell-crank lever, and extending beside the arm 13. The outer end of the lever arm 30 is provided with a hand grip member 31, preferably offset as shown by Fig. 1, the arrangement being such that when the outer jaw is engaged with a valve *a*, and the inner jaw is in position to lift the spring *c*, the grip member 31 is spaced from the grip 100 105 110

member 14, the two members being arranged to be grasped by one hand, so that when the hand is contracted, the lever 30 and the inner jaw are moved to lift the spring.

5 The outer jaw body 12 and the lever arm 30 are provided with complementary members adapted to secure the lever-arm and inner jaw in a fixed position relatively to the outer jaw when the spring is lifted. Said members are preferably embodied in a series of 10 ratchet teeth 33 on the outer jaw body 12, and a pawl 34 pivoted at 35 to the lever arm 30, and adapted to automatically engage one of the ratchet teeth when the inner jaw is in 15 position to raise the spring.

I am not limited to the described adjustability of the recess 18 of the inner jaw, and may make said jaw as a single part which is integral with the lever arm 30, as indicated by Fig. 4.

Fig. 5 shows an embodiment of the invention in which a portion of the arm 13^a of the outer jaw 12^a constitutes a grip member, and a portion of the lever arm 30^a of the inner jaw constitutes the other grip member, the pawl 34^a being arranged to engage ratchet teeth on an extension 13^b of the arm 13^a. The pointed valve-engaging end 16^a is in this case integral with the outer jaw.

30 Each of the described embodiments comprises a body portion which includes the outer jaw and an arm, as 13 or 13^a, rigidly connected with the outer jaw and arranged at an angle therewith, said arm projecting downwardly from the outer jaw, and a bell-crank lever fulcrumed at 23 on the lower end of said arm, one bell-crank lever arm constituting a spring-lifting inner jaw, while the other arm 30, or 30^a, is a jaw-operating arm. The bell-crank lever is 35 movable on its fulcrum with inconsiderable frictional resistance, and the number of essential parts is reduced to a minimum.

It will be seen that in each embodiment the arrangement is such that the operator is 40 enabled, by the use of one hand, to swing the bell-crank lever in the direction required to lift the spring, and to hold the spring lifted, or compressed, until the pawl engages 45 one of the ratchet teeth.

I claim:

1. A valve spring lifter, comprising a body portion, which includes an outer jaw, having a terminal formed to be seated on a

55 puppet valve, and an arm rigidly connected with said outer jaw, and arranged at an angle therewith, said arm projecting downwardly from the outer jaw, and a bell-crank lever fulcrumed on the lower end of said arm, one bell-crank lever arm constituting a 60 spring-lifting inner jaw, and the other bell-crank lever arm being a jaw-operating arm, said body portion and bell-crank lever including hand grip members, operable by one hand of the operator to lift the spring of 65 said valve, and hold said spring lifted.

2. A valve spring lifter substantially as specified by claim 1, said body portion and bell-crank lever being provided with complementary interengaging members to maintain the bell-crank lever in its spring-lifting position.

3. A valve spring lifter substantially as specified by claim 1, the body portion being provided with ratchet teeth, and the bell-crank lever being provided with a pawl adapted to engage either of said teeth, and thereby maintain the lever in its spring-lifting position.

4. A valve spring lifter substantially as specified by claim 1, the lever arm forming the inner jaw including two relatively movable fingers forming a stem-receiving recess, and provided with overlapping ears having oblique slots, and a bolt passing through said slots, and having clamping means, the said slots being in different angular positions, and the bolt being adjustable to vary the width of said recess.

5. A valve spring lifter comprising an 90 outer jaw formed to be seated on a puppet valve, and provided with an arm and with a hand grip member projecting in opposite directions from the jaw, and an inner jaw formed to lift the spring on the stem of 95 said valve, and pivoted to said arm, said inner jaw being provided with a lever having a hand grip member operatively related to the grip member on the outer jaw.

6. A valve spring lifter substantially as 100 specified by claim 5, the outer jaw being provided with ratchet teeth, and said lever arm with a pawl adapted to engage either of said teeth, and thereby maintain the inner jaw in its spring-lifting position.

In testimony whereof I have affixed my signature.

JOHN FABIEN DUBY.
